PUMPING APPARATUS

Filed March 26, 1931

UNITED STATES PATENT OFFICE

LEWIS F. V. DRAKE, OF NEW YORK, N. Y., ASSIGNOR TO SALVAGE PROCESS CORPORATION, OF NEW YORK, N. Y., A CORPORATION OF NEW YORK

PUMPING APPARATUS

Application filed March 26, 1931. Serial No. 525,359.

This invention relates to improvements in pumping apparatus and refers more particularly to an apparatus adapted for transferring viscous liquids such as heavy oils, sludge, molasses or like materials.

The novelty of the invention lies primarily in the mounting of duplicate sets of equipment upon a portable base such as a truck or railroad car, the equipment including a receptacle or container from which is exhausted the air by means of the vacuum pump, each vacuum pump being direct connected to a separate power source.

The equipment or apparatus utilizes the process described in the Wheeler Patents Nos. 1,405,173 and 1,480,482.

Fig. 1 is a plan view of the apparatus as mounted upon a railroad car.

Fig. 2 is a side elevational view of the car shown in Fig. 1.

Referring to the drawing, upon a railroad car 1 are mounted the tanks 2, 3, 4, and 5. These tanks are mounted upon blocks 6 and are held in place by means of steel straps 7. Between the tanks 2 and 3 is a suction cross-over line 8 and a vacuum cross-over line 9. The cross-over 8 is controlled by means of valves 10 and 11, while the cross-over line 9 is regulated by valves 12 and 13. Tanks 4 and 5 have a suction cross-over line 14, regulated by valves 15 and 16 and a vacuum cross-over pipe 17 regulated by valves 18 and 19.

All of the tanks are equipped with removable hand hold plates 20. Mounted centrally of the car are two vacuum pumps 21 and 22. Vacuum pump 21 is driven by a source of power which is designated as 23 and the vacuum pump 22 is driven by a separate source of power 24. These power sources may be electric motors, internal combustion engines, steam engines, or mechanism of any type having sufficient power to drive the vacuum pumps.

The vacuum pumps are equipped with water cooling lines 25. Vacuum pump 21 has a connection 26, with a cross-over line 9 and similar connection 27 connects the vacuum pump 22 with a cross-over line 17. Beneath the receptacles 2 and 3 is a drain manifold 28 which has connection with the bottom of

the two tanks. The pipes connecting the drain manifold 28 with the tanks are controlled by valves 29 and 30. A similar manifold 31 is positioned between the receptacles 4 and 5 and is controlled by valves 32 and 33. These manifolds are drained through outlet connections 34 and 35. Also, the two manifolds 28 and 31 are connected by a pipe 36. The two suction manifold or cross-over pipes 8 and 14 are equipped with a central T-connection to which are attached flexible suction hose lines 37 and 38.

In operation, assuming that the vacuum pump 21 is in use, either one or both of the receptacles 2 and 3 may be used by manipulation of the valves 12 and 13. The vacuum pump pulls a vacuum upon either or both of the tanks, exhausting the air from the tanks and creating a vacuum upon the suction cross-over pipe 8 and in the hose line 37. By applying the nozzle of the hose to the viscous liquid and permitting air to mix with the viscous material, an air emulsion containing relatively small particles of the material is drawn through the hose and the material accumulated in either or both of the tanks which are in use. After an accumulation has been built up in the tanks, the valves 10 and 11 are closed and compressed air or steam introduced through pipe connections 39 and 40, the latter regulated by valves 41 and 42. The air or steam line 39 is connected into the tanks 4 and 5 by pipe 43, regulated by valves 44 and 45. Air or steam is introduced into the pipe 39 from any convenient source through a connection 46 shown broken away in Fig. 2.

After an accumulation of the viscous material has been built up in either or both of the tanks 2 and 3, the vacuum pump is stopped, the valves 12 and 13 closed, and the drain valves 29 and 30 opened. Air or steam is then introduced into the tanks, creating pressure upon the tanks and forcing the materials out through the drain lines. Solid objects accumulating in the tanks may be removed by means of the hand hold plates 20.

By mounting duplicate equipment and connecting the equipment up in the manner shown, continuous operation may be carried

on without interruption, and the intercommunication of the equipment, including the tanks and pumps, permits the use of the equipment in almost any desired manner.

5. The equipment is particularly adapted for cleaning oil tanks of ships, reservoirs, tanks, and containers in which have accumulated viscous substances such as bottom settling in crude oil tanks, sludge and heavy asphaltic bottoms which tend to settle from petroleum products in refineries, tank farms or in manufacturing establishments.

I claim as my invention:

15. 1. Portable pumping apparatus comprising a movable base, a prime mover, a vacuum pump driven thereby, a plurality of tanks, valved inlet openings therefor, valved outlet openings therefor, a manifold connecting said inlet openings, a manifold connected to said pump connecting said outlet openings, a duct connected to said inlet manifold, whereby said valves may be manipulated in order that said tanks may be selectively filled either individually or in a group.

25. 2. Portable pumping apparatus comprising a movable base, a prime mover, a vacuum pump driven thereby, a plurality of tanks, valved inlet openings therefor, valved outlet openings therefor, a manifold connecting said inlet openings, a manifold connected to said pump connecting said outlet openings, a duct connected to said inlet manifold, whereby said valves may be manipulated in order that said tanks may be selectively filled either individually or in a group, means for putting said tanks under pressure and drain means through which matter within said tanks may be discharged by said pressure.

40. 3. In combination with a vehicle, a platform, a plurality of tanks, means for mounting said tanks on said platform, a prime mover mounted thereon, a vacuum pump driven by said prime mover, valved inlet openings for said tanks, valved outlet openings for said tanks, a manifold connecting said inlet openings a manifold connected to said pump connecting said outlet openings, a duct connected to said inlet manifold, whereby said valves may be manipulated in order that said tanks may be selectively filled either individually or in a group.

45. 4. In combination with a vehicle, a platform, a plurality of tanks, means for mounting said tanks on said platform, a prime mover mounted thereon, a vacuum pump driven by said prime mover, valved inlet openings for said tanks, valved outlet openings for said tanks, a manifold connecting said inlet openings, a manifold connected to said pump connecting said outlet openings, a duct connected to said inlet manifold, whereby said tanks may be selectively filled either individually or in a group, means for putting said tanks under pressure and drain lines

through which matter within said tanks may be discharged by said pressure.

5. Portable pumping apparatus comprising a movable base, a prime mover, a vacuum pump driven thereby, a plurality of tanks, valved inlet openings therefor, valved outlet openings therefor, a manifold connecting said inlet openings, a manifold connected to said pump connecting said outlet openings, a duct connected to said inlet manifold, whereby said valves may be manipulated in order that said tanks may be selectively filled either individually or in a group, combination air and steam lines connected to said tanks for imposing pressure thereon and drain lines for discharging matter within said tanks under said pressure.

In testimony whereof I affix my signature.

LEWIS F. V. DRAKE.
